Assistant Examiner — Edward P Jones

(57) **CLAIM**

The ornamental design for dental CT scanner, as shown and described.

DESCRIPTION

1. Dental CT scanner

1.1 : Perspective

1.2 : Perspective

1.3 : Perspective

1.4 : Perspective

1.5 : Front

1.6 : Back

1.7 : Top

1.8 : Left

1.9 : Right

1.10 : Enlarged

1.11 : Enlarged

1.12 : Enlarged

Reproduction 1.10 is an enlarged view of a portion labeled “10” in reproduction 1.2; reproduction 1.11 is an enlarged view of a portion labeled “11” in reproduction 1.2; reproduction 1.12 is an enlarged view of a portion labeled “12” in reproduction 1.3; the parts shown in broken lines are for illustrative purposes only and form no parts of the claimed design.

1 Claim, 12 Drawing Sheets
